(57) **CLAIM**

The ornamental design for air circulation cup holder, as shown and described.

DESCRIPTION

FIG. 1 is a perspective view of the air circulation cup holder; FIG. 2 is a front plan view thereof, which is a mirror image of the back plan view thereof; FIG. 3 is a side view thereof, which is a mirror image of all side views thereof; FIG. 4 is a top plan view thereof, wherein dotted lines illustrate an interior pedestal; and, FIG. 5 is a bottom plan thereof, wherein the dotted lines illustrate an interior pedestal, holes, and tabs.
